V. L. KAEHLER

TABLE FOR USE OVER RADIATORS

Filed March 3, 1923

V. L. Kaehter

BY
Watson E. Coleman
ATTORNEY.

UNITED STATES PATENT OFFICE.

VICTORIA L. KAEHLER, OF RICHMOND, VIRGINIA, ASSIGNOR OF ONE-HALF TO
JOSEPHINE L. JOHNSON, OF PHILADELPHIA, PENNSYLVANIA.

TABLE FOR USE OVER RADIATORS.

Application filed March 3, 1923. Serial No. 622,580.

To all whom it may concern:

Be it known that I, VICTORIA L. KAEHLER, a citizen of the United States, residing at Richmond, in the county of Henrico and State of Virginia, have invented certain new and useful Improvements in Tables for Use Over Radiators, of which the following is a specification, reference being had to the accompanying drawings.

10 This invention relates to articles of furniture, and particularly to tables.

The general object of this invention is to provide a table which is adapted to be disposed over a radiator and which is so constructed that it will deflect the heat from the radiator outward into the room and which is further so constructed that the table will not be affected by the heat given off from the radiator.

20 A further object is to provide a table of this character having a top and a lower wall separated from the top to form an air space between the lower wall and top, this lower wall being of metal and coated with asbestos or other nonconductor of heat and being disposed immediately over the radiator, the table being formed with air ducts whereby a constant circulation of air may be secured between the sheet metal wall and the table 25 top and in the air space so as to prevent the overheating of the table and prevent any warping of the table top.

30 A still further object is to so connect the metallic lower wall to the back rail and the front rail of the table as to prevent the passage of air around the joint and into the air space.

35 Other objects will appear in the course of the following description.

40 My invention is illustrated in the accompanying drawings, wherein:—

Figure 1 is a sectional perspective view of my improved table;

45 Figure 2 is a transverse section from front to rear;

Figure 3 is a longitudinal sectional view of the table.

50 Referring to these drawings, 10 designates a table top, 11 the front rail thereof, 12 the back rail thereof, and 13 the legs. This table may be of any suitable design and construction and may be made of any suitable material, preferably of wood. The back rail 12 is deeper than the front rail 11 and 55 both the back rail and the front rail are

formed with longitudinally extending openings 14 through which air may pass. As illustrated, the back and front rails are cut away adjacent their upper edges so that the top 10 of the table forms the upper wall of the air passages or ducts 14. There may be as many of these ducts as desired and the ducts might also be made in the end rails of the table if desired. Preferably, however, they will be in the front and rear rails. 60

Disposed below the table top is a wall 15 of thin sheet metal, preferably steel, and cemented to the inner or upper face of this sheet metal wall is asbestos 16 or other suitable non-heat-conducting material. The front rail 11 is grooved, as at 17, to receive the forward edge of the sheet metal 15 and the wall 12 at its lower end is downwardly and rearwardly grooved, as at 18, to receive the rear edge of the sheet metal. As illustrated in Figure 1, the sheet metal extends horizontally rearward from the front wall and then gradually curves down so as to more or less fit the curvature of the upper portion of an ordinary steam or hot water 70 radiator, designated A in Figure 2. The end rails of the table are also preferably grooved so as to receive the ends of the sheet 15, as at 19, see Figure 3.

75 It will be seen that with this construction an air chamber 20 is formed between the sheet metal 15 and the table top and that the ducts 14 permit a constant circulation of cool air through this air space. It will likewise be seen that the curved bottom wall 15 acts to deflect the heat of the radiator outward into the room.

80 One of the chief difficulties with radiators and other heating appliances is that the heat rises upward in a column and accumulates in the upper portion of the room and hence it is most desirable to provide means for causing the deflection of this heat outward into the room and its general circulation in the lower portion of the room before it rises. 85 This is secured by this table. At the same time the table top and the other parts of the table are thoroughly insulated from the radiator so that they are not affected thereby. 100

105 It will be understood that in place of sheet steel sheet metal of any desired character may be used and that I do not wish to be limited to the use of sheet metal for the wall 15, as it might be made of thin wood 110

properly treated and covered with asbestos, or of indurated fiber or the like. Any other heat insulating substance may be used in place of asbestos where desired, and the 5 table comprising the rails 11, the top 10, the legs 13, etc., may be made of wood, iron, steel or any metal or other substance desired. Preferably there will be a hard oil finish on all the outside parts and the entire 10 inside of the table will be given one coat of metallic paint.

It will be understood that this table saves space, inasmuch as the table does not have to be set in front of a radiator or away 15 from the radiator but may be set over the radiator. As stated, the table not only saves space but also causes the heat to be deflected outward into the room.

I claim:—

- 20 1. A table adapted to be disposed over a radiator comprising a table top, side and end rails, and legs, there being a heat insulating wall carried by the side and end rails below the top and there being an air 25 space between the said wall and the top, certain of the rails being formed with longitudinally extending air ducts through which air may pass into the air space formed between the wall and the top of the table.
- 30 2. A table having a top, end rails, a front rail, and a back rail, the back rail extending downward below the front rail, certain of the rails having longitudinally extending air ducts cut therethrough and all of said rails 35 along their lower margins being formed with grooves, and a non-heat-conducting wall having its margins disposed in said

grooves, the wall extending rearward and downward to approximately fit over a radiator and deflect the heat of the radiator outward. 40

3. A table of the character described comprising a top, end rails, a front rail, and a back rail, the back rail extending downward below the front rail and the front and back 45 rails being provided with longitudinally extending slots constituting air ducts, the inner faces of the end rails, the front rail, and the back rail having longitudinally extending grooves, a metallic wall having its 50 margins disposed in said grooves and having its inner face coated with a non-heat-conducting material, said metallic wall extending rearward from the front rail and then rearward and downward in a curve adapted to approximately fit the curvature of a 55 radiator.

4. An article of furniture adapted to be placed over a radiator and including a top, end members, front and rear members, and 60 a wall carried by said end, front and rear members, the wall being non-heat-conducting and being spaced from the top to form an air chamber between the wall and the top, there being openings through certain of 65 said members to permit the circulation of air between the top and said wall, to thereby prevent the heating of the top, the wall being downwardly and rearwardly extended to form a heat deflector. 70

In testimony whereof I hereunto affix my signature.

VICTORIA L. KAEHLER.
